PORTHOLE COVER CONSTRUCTION

John A. Elfstrom, Staten Island, N. Y.

Application July 21, 1938, Serial No. 220,491

1 Claim. (Cl. 114—178)

The invention relates to improvements in the construction of closures for portholes on ships, aircraft and the like.

Objects and advantages of the invention will be set forth in part hereinafter and in part will be obvious herefrom, or may be learned by practice with the invention, the same being realized and attained by means of the instrumentalities and combinations pointed out in the appended claim.

The invention consists in the novel parts, constructions, arrangements, combinations and improvements herein shown and described.

The accompanying drawing, referred to herein and constituting a part hereof, illustrates one embodiment of the invention, and together with the description, serves to explain the principles of the invention.

Of the drawing:

Fig. 1 is a front elevation of a construction embodying the invention;

Fig. 2 is a transverse vertical section on line 2—2 of Fig. 1;

Fig. 3 is a top plan view of the construction shown in Fig. 1;

Fig. 4 is a detail in elevation of the fixed port-hole frame on a smaller scale than Fig. 1;

Fig. 5 is a similar detail of the locking ring; and

Fig. 6 is a perspective detail of a locking tool.

The invention is directed to providing an improved and novel construction for the cover or closure for a porthole such as is usually found in the side of a ship, and also to novel and useful means for readily, accurately and securely fastening such covers in place and unfastening same. One object of the invention is to enable a ship's porthole cover to be fastened and unfastened rapidly and also to secure the cover firmly in place without imposing any torsion or strain on the lens of glass mounted in the cover. The invention also provides novel means for mounting and coordinating the closing and opening operations of an outer darkening cover or "battle" cover with the closure of the lens-supporting frame and cover.

The construction provided by the invention is relatively simple and inexpensive to manufacture, comprises a minimum of parts, and can be made very strong and rigid from relatively light metal and parts. For this reason it is adapted for use on yachts and small vessels and also on aircraft, although it is also well adapted for general application for larger vessels.

Referring now in detail to the present preferred embodiment of the invention illustrated by way of example in the accompanying drawing, the porthole or opening P is formed in a frame comprising an annular, generally flat casting I which is securely fastened to the inner wall W of the ship by bolts or other suitable means. A suitable flange 20 projects outwardly from the outward

face of the casting to define the outer edge of the porthole, while the casting projects inwardly with an opening 21 of slightly greater diameter. About the cylindrical surface 21 the casting I is formed as a thickened ring 22 tapering from the flat surface 23 upwardly and inwardly to form a flat edge or shoulder 24 along the inner surface of the casting I. An annular groove 25 is formed in said surface 24 and seated therein is a cushioning gasket 26 of rubber or the like.

A lens-supporting cover, comprising primarily a cylindrical frame 3, is mounted for pivotal movement toward and away from the casting I. As embodied, said frame 3 is provided with outwardly projecting hinge lugs 3c which are bored at their outer ends to receive and rotate about a hinge pin 9. Said hinge pin is loosely supported in fixed hinge lugs 14 which extend upwardly from the outer flat surface 23 of casting I and are so spaced that the movable hinge lugs 3c lie against their inner faces. The hinge pin 9 is removably held in place, as by cotter pins at either end. It will be clear from the drawing that frame 3 is thus swingable from a plane parallel to and contacting with the inner edge 24 of casting I (in which position the bottom edge of the cylinder 3 lies against the rubber gasket 26) to an outer or uncovered position 180 degrees opposite. A glass lens L is suitably seated in a cylindrical seat 3b on the interior face of the frame 3 and is tightly held therein by a screw-threaded ring 3a which cooperates with interior threading on the inner face of the cylinder 3 below the lens seat 3b.

The invention comprises novel means for fastening the lens frame or cylinder 3 in closed position with respect to the casting I whereby same may be very readily secured together and as readily unlocked by a single, unidirectional movement. As embodied a ring 2 is screw-threaded on its inner surface to engage conforming threads 30 on the outer surface of the cylindrical frame 3. Said ring 2 tapers downwardly and outwardly to overlie the conformably tapered portion 22 of the casting I. A plurality of lands 35 are formed along the bottom face of ring 2 and project radially inwardly so as to lie but a short space from the inclined face 22 of the casting I. Said lands are themselves inclined at the same angle as the face 22 and are spaced equally about the bottom of the ring 2 so as to occupy about one-half of the circumference thereof. As shown said lands are four in number, but may comprise a greater or a lesser number if desired. The inclined surface 22 of the fixed casting I is also provided with a plurality of outwardly extending lands 36 which conform in number and size to the lands 35, but immediately overlie same so that the lands 35 are rotatable with the ring 2 relatively to the overlying lands 36 but with a relatively close sliding

contact between the bottom surface of lands 36 and the top surface of the lands 35. It will be understood that the ring 2 may be rotated in limited amount so that in one position the lands 35 fit between the lands 36 while in the other position, lands 35 underlie the lands 36 as shown in Fig. 5, thereby to firmly lock and hold the cylinder 3 to the casting 1.

Means are provided for conveniently imparting the necessary rotational movement to ring 2 for the purpose of locking and unlocking same from the casting 1. As embodied the lower and outer surface of ring 2 is provided with a plurality of bevelled gear teeth 40 extending around the entire circumference. A suitable tool or wrench 17 is provided with a circular head 18 having gear teeth 19 conforming to the teeth 40 on the ring 2. The shaft of the tool projects downwardly at 45 to form a stud adapted to be 20 socketed in any one of a plurality of circular sockets 47 formed at a desired number of points in the outwardly-extending, flat portion of the casting 1. It will be clear that by seating the stud 45 in any one of the seven sockets 47, the teeth 19 will engage the teeth 40 of the ring 2 to permit rotation thereof for locking and unlocking movement. While ordinarily only a single wrench need be used and it may be positioned in any one of the sockets 47, the plurality of spaced sockets 47 permits a multiplied application of turning force when same should be necessary as in cases where the closure has become stuck or rusted from lack of use. In practice the amount of rotation given to the ring 2 in order 30 to lock and unlock same will preferably be one-half or less of the arc defined by one of the lands, that amount of overlap being adequate to give a good locking action. Any greater rotation of the ring 2 is prevented by a suitable stop, such as the pin 16 formed at the edge of one of the lands 36 40 and projecting below same to contact with the edge of the conforming land 35.

In accordance with one feature of the invention, the locking movement of the ring 2 is intended and designed to effect a very tight closure 45 of the cylinder 3 into the socket 25 and against the rubber gasket 26. Accordingly the sense of the threading 30 between the cylinder 3 and ring 2 is such that locking rotation of the ring tends to draw the cylinder 3 downwardly and into very 50 tight contact with the gasket 26. The threading 30 may be a multiple thread so as to permit adjustment of the ring 2 with respect to the cylinder 3 to advance or retract the ring with respect to the cylinder, thereby to vary the tightness of 55 the closure. This feature is particularly important to compensate for wearing away of the gasket or shrinkage or compression of same after long use.

Means are provided for accurately retaining the 60 ring 2 in position to seat in closing position without clashing of the lands 35 and 36 when the ring 3 and its attached parts is swung to closing from the open position. As embodied a guiding fin 8 is formed to project upwardly from the casting 1 and extend inwardly toward the toothed portion of the ring 2. Said fin is bored to pass the hinge pin 9 and is provided with an arcuate surface which projects to lie between any two of the bevelled teeth 40 on the ring 2. To insure the ring 2 stopping in the proper position, whereby the lands 35 and 36 are in a non-engaging relation and a space between the teeth

40 in proper alignment with the fin 8, there is provided a stop pin 50 which is set into the portion 22 of the frame 1 so as to be in the path of rotation of the lands 35 carried on ring 2. Thus upon swinging open the ring 2 and cylinder 3, the fin 8 guides the swinging movement but prevents rotation of the ring 2 with respect to the cylinder 3 and upon return thereof to closed position insures that the lands will not clash or overlap.

It will be noted that the level of the hinge pin or axis 9 is substantially in the same plane as the rubber gasket 26. This construction prevents any swiping or bending movement with respect to the gasket upon closing of the port, as is normally the case with portholes of present construction, in which the axis of the hinged cover is above the plane of the gasket and causes an uneven pressure and swiping or digging in closing, which tend to unseat or tear the gasket.

The invention further provides a novel construction and arrangement of means for combining a darkening or battle cover with the above described mechanism. As embodied a darkening cover 4 formed as a disc casting is mounted to overlie the upper edge of the cylinder 3 and is hinged for relative opening and closing movement with respect thereto. The bottom face of this board is grooved at 5 near its periphery to receive a rubber gasket which overlies and seats upon the upper ridged edge of the cylinder 3.

The embodied means for hingedly supporting the disc 4 with respect to the frame 3 and the casting 1 comprises a pair of outwardly extending hinged arms 4a which are bored to rotate about the hinge pin 9 just within the hinge arms 3c. Means for fastening the cover disc 4 to the lens frame 3 comprises a hook 13 projecting from the periphery of the cylinder 3 and a hasp 12 pivotally formed on the draw bolt 10. Said bolt is 40 pivotally mounted on the periphery of the disc 4 and is locked in closing position by a toggle action in a known manner. Thus the darkening cover 4, when in closed position, may be released and moved together with the lens frame 3 as a unit simply by release of the locking ring 2 as above described. On the other hand by releasing the hasp 12 by pulling the ring 11, the cover 4 may be separately disengaged and swung out of the way while the lens frame 3 remains locked. 45

The invention in its broader aspects is not limited to the specific mechanisms shown and described but departures may be made therefrom within the scope of the accompanying claim with out departing from the principles of the invention and without sacrificing its chief advantages. 55

What I claim is:

A porthole closure including in combination a fixed frame having a port therein, a lens frame hingedly mounted with respect to the porthole frame and movable into and out of parallelism therewith, a rotatable locking ring mounted on the lens frame and surrounding a portion of the fixed frame, one or more lands on said surrounded portion of the fixed frame projecting radially therefrom, and conforming lands on the rotatable locking ring adapted to underlie said first-mentioned lands and movable into and out of locking engagement therewith upon rotation of the locking ring, the axis of said lens frame being substantially in the same plane as the contacting face of said frame with that of the fixed frame. 70
